Levi Barnell

The schedule referred to in this Letters Patent is not making part of the same containing a description in the words of the said Levi Barnell himself of his improvement in the machine for propelling boats on canals and shoal waters.

To all to whom these presents shall come:

Be it known that I, Levi Barnell of Elizabethtown in the County of Lorain and State of Ohio have invented a new and useful improvement in a machine for propelling boats on canals and shoal water and that the following is a full and exact description of the construction and operation of said machine as invented by me. A sun wheel A, eight or nine feet in diameter, from two to three inches thick formed into notches or grooves on the periphery, and if necessary fitted with iron, has its eyes hung upon bearings &c. at the end of a substantial bar B. about sixteen feet long. Said bar set the wheel A. and being so directed as to pass each side of said wheel. The opposite end of said bar has also a shaft B. passing through it with cranks C. at right angles to opposite sides of said bar, from these cranks to other cranks D. corresponding therewith on opposite sides of the wheel A. pins connecting rods, so that the revolving of the shaft B. at the end of the bar B. opposite will cause the wheel A. to revolve.

The wheel A. is intended to traverse the canal cutting the water in its path, and of sufficient weight to be loaded, so to take hold upon the bottom of the canal and rising rapidly, falling freely accommodates the wheel A. to the bottom, be it ever so uneven. The wheel being suspended by suitable braces D. & guides C. forms a simple & efficient propeller adaptable to craft of any size in shoal water, and may be used separately or in connection with ordinary paddle wheel boats. Witnessed this 3rd day of January 1843. Levi Barnell
